CLAIM

The ornamental design for a fish feeding apparatus, as shown and described.

DESCRIPTION

FIG. 1 is a perspective view of a fish feeding apparatus.

FIG. 2 is a front side view of the fish feeding apparatus of FIG. 1.

FIG. 3 is a right side view of the fish feeding apparatus of FIG. 1.

FIG. 4 is a top view of the fish feeding apparatus of FIG. 1.

FIG. 5 is a bottom view of the fish feeding apparatus of FIG. 1.

FIG. 6 is an exploded view of the fish feeding apparatus of FIG. 1.

FIG. 7 is a perspective view of the clip component of the fish feeding apparatus, shown separately for clarity.

FIG. 8 is a front side view of the clip of FIG. 7.

FIG. 9 is a right side view of the clip of FIG. 7.

FIG. 10 is a top view of the the clip of FIG. 7.

FIG. 11 is a bottom view of the clip of FIG. 7; and, FIG. 12 is a right view of the clip of FIG. 7 in the open position.

The broken lines in the figures show portions illustrating environmental structures that form no part of the claimed design.
